1,965,722

HOOD AND REFLECTOR CONSTRUCTION

Paul D. Phillips, Elmhurst, Ill., assignor to Benjamin Electric Mfg. Company, Des Plaines, Ill., a corporation of Illinois

Application January 26, 1933, Serial No. 653,653

16 Claims. (Cl. 240—143)

My invention relates to a hood and reflector construction.

An object of my invention is to provide an electric-light socket water-proof and otherwise proof against the weather elements.

Another object of my invention is to provide an electric-light-socket hood adapted to receive a socket and a reflector, said socket and reflector being connected to the hood independently, and being independently, conveniently, and readily removed or attached to the hood.

A further object of my invention is to provide an electric-light-socket hood with a socket and a reflector attached thereto, having a means for readily loosening the reflector for adjustment, said adjustment being made entirely independent of the light socket.

A still further object of my invention is to provide electric-light-socket constructions adapting small and large sockets to a standard size hood.

Providing a construction for making readily accessible the mounting screws of large sockets is still another object of my invention.

Other objects will be evident from the following description and appended claims:

Figure 1 is a cross-sectional view of my invention assembled;

Fig. 2 is a bottom view of my invention shown in Fig. 1;

Fig. 3 is another form of my invention;

Fig. 4 is a bottom view of my invention shown in Fig. 3;

Fig. 5 is a top view of my invention shown in Fig. 3; and

Fig. 6 is a broken sectional view taken on the plane 6—6 in Fig. 5.

In referring more specifically to the drawing, a metal hood 1, illustrated in Figs. 1 and 2, is provided with a circumferential skirt 2 for weather-proofing the connection between the hood 1 and the reflector 3. The hood is provided further with two bosses 4, drilled and threaded to support the screws 5 attaching the light-socket 6 to the hood 1.

A threaded conduit opening 7 is provided at the side of the hood, and a drilled projection 8 at the top of the hood is provided for a suspension cord (not shown) to give necessary added support in installations where the conduit (not shown) entering the hood through the opening 7 is insufficient.

Inside the skirt 2, riveted at 9 and spaced from the inside of the skirt by an embossment 10 extending inwardly from the hood and being a part of it, is a band clamp 11 extending slightly more

than half-way around the inner circumference of the skirt and having three embossments 12 extending outwardly therefrom to act as supporting ledges for the reduced neck 13 of the reflector 3.

The band clamp 11, while rigidly supported to the hood and kept in assembly with respect thereto by the rivet 9, is further supported with respect to the hood by the screws 14 which extend through an oversize opening 15 in the skirt 2, 65 and screw into a threaded opening in the band clamp 11.

This construction provides a means for quickly attaching to or detaching the reflector 3 from the hood 1 by loosening or tightening the screws 70 and then slipping the reflector on or off over the embossments 12.

It is evident from the construction shown that the socket 6 can be unscrewed and removed from the hood 1 and that the reverse operation can 75 be performed without removing or even touching the reflector 3. Likewise, the reflector is independently attached to the hood and can be removed, assembled, or adjusted without touching the socket unit 6.

In Figs. 3, 4, 5 and 6 is depicted a large and different type of socket 6a adapted to be used in combination with the hood and reflector shown in Fig. 1. The socket, shown in Figs. 1 and 2, is provided with a pair of ears 16 apertured for 85 the attaching screws 5. However, in the case of a larger socket represented by Figs. 3, 4, 5 and 6, a similar construction would be prohibitive for use with the same size reflector as that delineated in Fig. 1. Therefore, I have provided a construction, shown in detail in Fig. 6, to allow the screws, which hold the socket with respect to the hood, to be removed and thereby to permit the socket 90 to be removed independently of the reflector.

Two slots 17 diametrically opposite are provided 95 in the side of the socket 6a; and, to permit convenient access to the screws 5a, a diagonal recess 18 is provided. Such construction allows a screw-driver to be conveniently manipulated between the reflector and the socket while the reflector is 100 in place and attached to the hood. The larger socket 6a is provided with niches 19 positioned to register with the band-clamp screws 14, which screws would otherwise be obstructed due to the little space left between the outer wall of the 105 larger socket and the band clamp. A reduced portion 20 is provided in the socket 6a to permit its fitting inside the band clamp 11.

While the hood construction shown in Fig. 1 is typical of an elbow fitting, it is apparent that 110

the conduit opening could lead in from any angle in any plane and that such differences would be obvious modifications of my invention.

Further modifications will be apparent to those skilled in the art and it is desired, therefore, that the invention be limited only by the prior art and the scope of the appended claims.

Having thus described my invention, what I claim and desire to secure by Letters Patent is:

10. 1. A shade support comprising a sleeve member, a resilient band positioned inside said sleeve and spaced therefrom, means for fastening said band intermediate the ends thereof to said sleeve, and means for moving the ends of said band toward and away from said sleeve to provide a clamping action.
20. 2. A shade support comprising a hood having a skirt portion, a resilient band positioned within said skirt portion and spaced therefrom, said band being secured intermediate the ends thereof to said skirt portion, and means for moving the ends of said band toward and away from said skirt portion to provide a clamping action.
25. 3. A shade support comprising a hood having a skirt portion, a resilient band positioned within said skirt portion and substantially uniformly spaced therefrom, said band being secured intermediate the ends thereof to said skirt portion, and means for moving the ends of said band toward and away from said skirt portion to provide a clamping action.
35. 4. A shade support comprising a hood having a skirt portion, a resilient band positioned within said skirt portion and mounted substantially concentric therewith, said band being secured intermediate the ends thereof to said skirt portion, and means for moving the ends of said band toward and away from said skirt portion to provide a clamping action.
40. 5. A shade support comprising a hood having a skirt portion, a resilient band positioned within said skirt portion and spaced therefrom, said band being secured intermediate the ends thereof to said skirt portion, and adjustable means for moving the ends of said band toward and away from said skirt portion to provide a clamping action.
50. 6. A shade support comprising a hood having a skirt portion, a resilient band positioned within said skirt portion and spaced therefrom, said band being secured intermediate the ends thereof to said skirt portion and spaced therefrom having projecting portions extending toward said skirt portion, and means for moving the ends of said band toward and away from said skirt portion to provide a clamping action.
60. 7. A shade support comprising a hood having a skirt portion, a resilient band positioned within said skirt portion and spaced therefrom, said band extending outwardly beyond the edge of said skirt portion and being secured intermediate the ends thereof to said skirt portion, and means for moving the ends of said band toward and away from said skirt to provide a clamping action.
65. 8. A shade support comprising a hood having a skirt portion, a resilient band positioned within said skirt portion, said band extending outwardly beyond said skirt portion and having projections thereon extending toward said skirt portion, means for securing said band intermediate the ends thereof to said skirt portion, and means for moving the ends of said band toward and away from said skirt portion to provide a clamping action.
75. 9. A shade support comprising a sleeve mem-

ber, a resilient band positioned within said sleeve and spaced therefrom, apertures in said sleeve member, screws loosely mounted in said apertures, threaded openings in said band substantially opposite said apertures into which said screws are adapted to thread whereby the tightening of said screws acts to move said band toward said sleeve.

10. A shade support comprising a hood having a skirt portion, a resilient band positioned within said skirt portion and spaced substantially equidistant therefrom, said band being secured intermediate the ends thereof to said skirt portion and being provided with threaded openings adjacent the ends thereof, apertures of a larger size in said skirt substantially opposite said openings, and screws for loosely fitting in said apertures and threading into said threaded openings whereby the tightening of the screws will move said band toward said skirt portion.

11. A shade support comprising a hood having an annular skirt portion, a resilient band in the form of a split ring with the ends separated from each other positioned within said skirt portion and being a distance therefrom sufficient to permit the insertion of the neck of a hood between said band and said skirt portion, said band being secured at a point substantially midway between the ends thereof to said skirt portion, and screws loosely mounted in said skirt portion and threading into said band adjacent the ends thereof whereby rotation of said screws serves to move the said band toward said skirt portion.

12. A lighting construction comprising a hood having a skirt portion, a resilient band positioned within said skirt portion and spaced therefrom, means for moving the ends of said band toward and away from said skirt portion to detachably secure a shade to said hood, a socket for fitting within said hood and said band, the portion of said socket fitting within said band having a diameter only slightly smaller than the inner diameter of said band, said socket having longitudinally extending grooves in the sides thereof with screws positioned at the inner end of said grooves for threading into said hood to secure said socket therein, said grooves permitting the use of a screw driver to thread said screws into said hood when a shade is in place.

13. A lighting construction comprising a hood having an outwardly extending skirt portion, a lamp socket mounted on and underneath said hood, a reflector having a neck portion surrounding said socket, and means for securing said neck portion to said skirt portion, said neck portion having an annular flange at its upper end extending inwardly and downwardly and thence upwardly into said skirt portion whereby a weatherproof construction is obtained and whereby a hook may be engaged with the inwardly and downwardly portion of the flange for supporting the reflector during the enameling operation.

14. A lighting construction comprising a hood, a lamp socket mounted on and underneath said hood, a reflector having a neck portion surrounding said socket and secured to said hood, said neck portion having an annular flange extending inwardly and downwardly underneath said hood whereby a weatherproof construction is obtained and whereby a hook may be engaged with said inwardly and downwardly extending flange portion for supporting the reflector during the enameling operation.

15. A lighting construction comprising a hood

having a downwardly extending skirt portion, a lamp socket mounted on and underneath said lamp socket mounted on and underneath said hood, a reflector having a neck portion surrounding said socket, said neck portion having an annular inwardly extending flange at its upper end, and means for securing said reflector to said hood comprising a spring inside said skirt portion extending circumferentially thereof and having a portion for engaging underneath said inwardly 5 portion for engaging underneath said inwardly extending flange.

16. A lighting construction comprising a hood having a downwardly extending skirt portion, a lamp socket mounted on and underneath said hood, a reflector having a neck portion surrounding said socket, said neck portion having an annular inwardly extending flange at its upper end, and means for securing said reflector to said hood comprising a spring inside and skirt portion extending circumferentially thereof and having a portion for engaging underneath said inwardly extending flange, and means for drawing said spring outwardly to effect an engagement with 10 said flange. 80

16. A lighting construction comprising a hood having a downwardly extending skirt portion, a lamp socket mounted on and underneath said hood, a reflector having a neck portion surrounding said socket, said neck portion having an annular inwardly extending flange at its upper end, and means for securing said reflector to said hood comprising a spring inside and skirt portion extending circumferentially thereof and having a portion for engaging underneath said inwardly extending flange, and means for drawing said spring outwardly to effect an engagement with 15 said flange. 85

CERTIFICATE OF CORRECTION.

July 10, 1934.

Patent No. 1,965,722.

PAUL D. PHILLIPS.

It is hereby certified that error appears in the printed specification of the above numbered patent requiring correction as follows: Page 2, line 116, claim 12, for "sand" read said; and page 3, line 81, claim 16, for "and" read said; and that the said Letters Patent should be read with these corrections therein that the same may conform to the record of the case in the Patent Office.

Signed and sealed this 7th day of August, A. D. 1934.

Leslie Frazer

Acting Commissioner of Patents.
